FIG. 4.

Inventor:

EDWARD A. BOLE,

By

Mark Miller

Attorney.

UNITED STATES PATENT OFFICE.

EDWARD A. BOLE, OF LONG BEACH, CALIFORNIA.

CONVEYER.

Application filed June 2, 1924. Serial No. 717,836.

To all whom it may concern:

Be it known that I, EDWARD A. BOLE, a citizen of the United States, residing at Long Beach, in the county of Los Angeles and State of California, have invented certain new and useful Improvements in Conveyers, of which the following is a specification, reference being had therein to the accompanying drawing.

10 The present invention relates generally to conveyers, and aims to provide a novel and improved conveyer structure, adapted especially for draining sewage and removing the solid matter therefrom to be burned in an incinerator or otherwise disposed of.

Another object is the provision of such a conveyer comprising an endless conveyer member of novel construction having hinged screens to facilitate the cleaning thereof.

20 A further object is the provision of means for discharging air, steam, water or other fluid through the screens for cleaning them in a practical and effective manner.

A still further object is to improve the receiving end portion of the conveyer which is in the sump, whereby the sewage is properly delivered on the conveyer member, and whereby the receiving end portion of the conveyer structure can be raised for making 30 repairs or adjustments.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein—

Figure 1 is a side elevation of the improved conveyer, portions being broken away and shown in section.

Fig. 2 is a fragmentary end view looking in the direction of the arrow 2 in Fig. 1, on an enlarged scale.

Fig. 3 is a horizontal section on the line 3—3 of Fig. 2.

Fig. 4 is a plan view of the receiving end portion of the conveyer, on an enlarged scale.

Fig. 5 is a section on the line 5—5 of Fig. 1, on an enlarged scale.

Figs. 6 and 7 are cross sections on the re-

spective lines 6—6 and 7—7 of Fig. 1, on an 55 enlarged scale.

The conveyer is inclined, with its lower end portion within a sump 14 through which the sewage flows from the inlet 15 to the outlet 16, and the sump has a depression or 60 cavity 17 between the inlet and outlet in which the lower end of the conveyer is disposed.

The conveyer structure includes a suitable frame 18, which is inclined, and which is 65 supported by posts or standards 19 and 20. The frame has a loose receiving end section or portion 21, which is hingedly connected to the lower end of the main frame 18, so that the section 21 can be swung upwardly 70 and downwardly out of and into the depression 17.

The endless conveyer member which is mounted for circuitous movement on the inclined frame, comprises the endless sprocket 75 chains 23 at the opposite side edges, composed of links or bars hingedly connected together. Between the sprocket chains are the screens 24 of suitable mesh, which have frames 24, and the side members of the 80 frames have outturned flanges 25 which are pivotally connected, as at 26, with the pivots of the links of the chains 23, the frames 24 of the screen is trailing from the pivots or 85 hinges 26. The screen frames overlap at the upper run of the conveyer member, the rear free edge portion of each screen frame overlapping the hinged edge portion of the next screen frame in rear, whereby the solid matter will be carried upwardly by the screens. 90 The flanges 25 assist in preventing the matter on the screens from running over the side edges of the screen frames, said flanges projecting upwardly along the upper run of the 95 conveyer member.

The main frame 18 and section 21 have rollers 27 for guiding the sprocket chains 23 at their upper and lower runs, and polygonal sprocket wheels 28 and 29 are provided at the upper and lower limits of travel of 100 the conveyer member, over which the sprocket chains pass.

As shown, there are two companion conveyers disposed side by side, in order that either one can be used or both of them simultaneously. Also, one conveyer can be idle, for purpose of repairs, cleaning or adjustments, while the other is in operation, and 105

the two conveyers can be alternated, to provide for continuous operation.

The frame 18 of each conveyer has inclined rails 30', preferably of wood, below the lower run of the conveyer member, on which the rear ends of the flanges 25 can drag as the screen frames are moved downwardly into the sump.

The sprocket wheels 28 of each conveyer are mounted for rotation on a shaft 30 supported by the standards 20, the shafts 30 of the two conveyers being in alinement, as seen in Fig. 3. The shaft 30, for reasons which will appear hereinafter, is stationary, and the sprocket wheels 28 rotate on said shaft. In order to drive the conveyer member, sprocket wheels 31 are secured to the sprocket wheels 28 and sprocket chains 32 pass around the sprocket wheels 31 and sprocket wheels 33 secured on a drive shaft 34 journaled for rotation on the standards 20 above the corresponding sprocket wheels 28. The shaft 34 has a pulley wheel 35 to receive a belt driven by an engine or motor.

In order to clean the screens 24', air, steam, water or other fluid is delivered into each shaft 30 under pressure, said shaft being hollow or tubular, and a discharge nozzle 36 projects from the pipe and has a perforated T-head 37 directed downwardly toward the upper ends of the rails 30'. The fluid discharged from the spray head 37 will pass from within the conveyer member outwardly through the screens, as the screens move around the sprocket wheels 28, thereby cleaning the foreign matter from the screens, and the pressure of the fluid against the inner sides of the screens will also throw the screens away from the sprocket chains against the upper terminals of the rails 30', so that the sudden stopping of the screens by their contact with the rails 30' will assist in jarring or shocking loose the matter which may cling to the screens. This, in addition to the discharge of the fluid under pressure through the screens, will effectively clean the screens as they start downwardly.

As shown in Fig. 2, air under pressure is supplied into the shafts 30 by blowers 38 having the discharge pipes 39 connected to the outer ends of the shafts 30.

In order to dissolve oil, grease and similar substances, from the screens a solvent therefor can be supplied to the air, so as to be discharged through the screens. Thus, feeders 40 of any well known kind can be attached to the air delivery pipes 39 for feeding the solvent or solution to the air. Such feeders can be similar to those used for supplying chemicals or boiler compounds to water supplied to steam boilers, or the like, as well known.

The lower sprocket wheels 29 of each conveyer are secured upon a shaft 41 that is journaled for rotation at its ends in bearings

or slides 42 that are mounted for upward and downward sliding movement in the standards or posts 43 and 44 mounted in the sump 14. Said standards are channeled to receive the slides, and the intermediate standard 44 may be an I beam to accommodate the adjacent slides 42 of the two conveyers while the standards 43 are composed of channel irons. The slides 42 can thus move along the standards when the frame section 21 is swung upwardly and downwardly, and the section 21 has longitudinal slots 45 engaging the hinge pins 22, so as to permit of a sliding movement of the section 21 relatively to the main frame 18 when the section 21 is swung upwardly and downwardly, on account of the shaft 41 and slides 42 having a straight line motion along the standards 43 and 44.

A windlass is provided for raising the section 21 of each conveyer structure. Thus, a shaft 46 is journaled on the upper ends of the corresponding standards 43 and 44, and has drums or spools 47 on which chains or other flexible elements 48 are wound, the lower ends of said chains being connected to the corresponding slides 42. The shaft 46 has a crank 49 at its outer end or other means for rotating the shaft to wind the chains on the drums, so as to raise the section 21, as seen in dotted lines in Fig. 4, thereby permitting repairs or adjustments to be made without emptying the sump or taking down the conveyer structure. A ratchet device 50 is provided for preventing reverse rotation of the shaft 46 until it is desired to again lower the frame section 21.

In order to direct the sewage to the upper run of the conveyer member, vertical side plates 51 are provided above the section 21 of each conveyer structure, and said plates 51 are supported by suitable supports 52 secured to the section 21, with the lower edges of the plates 51 disposed between the chains 23 and flanges 25 of the screen frames 24. Strips 53 are secured to the inner sides of the plates 51 above the screen frames, and said strips have offset aprons 54 which depend and overlap the inner sides of the flanges 25, as seen in Fig. 6, thereby directing the sewage to the screens 24', the aprons 54 preventing the sewage from passing the side edges of the screen frames and also keeping the solid matter on the screens until raised out of the water. The sump 14 is provided with an abutment 55 therein, and said abutment extends to the standard 44, and also forms the channels 58 leading from the inlet 15 to the two conveyers. The plates 51 project beyond the lower end of the conveyer and overlap the sides of the channels 58, as seen in Fig. 4, so that the sewage flows from the channels 58 between the plates 51 to the conveyer members.

A plate 56 is disposed between each pair

of side plates 51 and is curved or arched over the sprocket wheels 29, the side edges of the plate 56 being secured to the strips 53. The projecting edge portion of the plate 56 is adapted to overlap and bear on the bottom of the sump 14 between the inlet 15 and depression 17, in order to prevent the sewage from passing under the lower end of the conveyer. In other words, the plate 56 deflects the sewage over such plate onto the upper run of the conveyer member, so that the sewage is strained, the water passing on through the screens, while the solid matter is carried upwardly with the screens on the upper run of the conveyer member.

A suitable gate 57 can be provided for each channel 58, in order that either channel can be closed, so that the sewage will pass through the other channel only. In this way, one conveyer can be in operation, while the other one is being repaired, cleaned or overhauled.

In operation, the sewage flows from the inlet 15 through the channel 58 between the plate 51 and over the plate 56 to the lower portion of the upper run of the conveyer member, the water passing through the screens 24, and said screens arrest the solid matter which is carried upwardly with the upper run of the conveyer member. The screens 24', as they pass around the sprocket wheels 28, are swung outwardly and downwardly away from the sprocket wheels 28 and chains 23, against the rails 30', and the fluid being discharged through the screens will assist in swinging the screens outwardly and will also dislodge the foreign matter and blow same from the screens. The fluid thus has a double function, namely, to swing the screens outwardly and downwardly so as to strike the rails 30' with a sudden jar to loosen the foreign matter, and, secondly, to discharge outwardly through the screens for loosening and removing the foreign matter therefrom. The screen frames 24 drag on the rails 30' in moving downwardly into the sump, and the screen frames move upwardly around the sprocket wheels 29 under the plate 56 and will overlap in moving upwardly from under the plate 56 so as to catch and elevate the solid matter of the sewage. When the gate 57 of one conveyer is closed, the section 21 can be raised, as seen in dotted lines in Fig. 4, for purpose of cleaning the device or making repairs or adjustments. The matter discharged from the upper end of the conveyer can be burned in an incinerator or otherwise disposed of.

Instead of using the tubular shaft 30 for supplying the fluid, it is possible to extend a pipe upwardly between the upper and lower runs of the conveyer member adjacent to or across the shaft 30 to the spray

head 37. In other words, the nozzle 36 can illustrate the end of a pipe extending between the sprocket wheels 28.

Having thus described the invention, what is claimed as new is:—

1. A conveyer including an endless conveyer member having screens hinged to swing outwardly, and means arranged to discharge fluid outwardly through said screens at the discharge portion of the conveyer to swing the screens outwardly and to simultaneously dislodge foreign matter therefrom. 70

2. A conveyer including an endless conveyer member having screens hinged to swing outwardly, a rail extending under said conveyer member for the contact of the screens, and means arranged to discharge fluid outwardly through the screens at the discharge portion of the conveyer to swing the screens outwardly against said rails and to simultaneously dislodge foreign matter from the screens. 80

3. A conveyer including endless sprocket chains, screens hingedly connected to said chains to swing outwardly, means for mounting the chains for circuitous movement including a tubular shaft and sprocket wheels for the chains on said shaft, a spray nozzle carried by said shaft between the sprocket wheel and arranged to discharge the fluid outwardly through the screens at the discharge portion of the conveyer to swing the screens outwardly and to simultaneously dislodge foreign matter therefrom, and means for supplying fluid into said shaft. 90

4. A conveyer including an endless conveyer member having screens hinged to swing outwardly, a rail underneath the conveyer member over which the screens are adapted to be dragged at the lower run of said member, means for mounting the conveyer member for circuitous movement including sprocket wheels at the receiving and discharge portions of the conveyer, and means between the sprocket wheels at the discharge portion of the conveyer arranged to discharge fluid outwardly through the screens to clean the screens and to simultaneously swing them outwardly so as to strike said rail. 105

5. A conveyer including an inclined frame having a lower end section connected thereto with a hinge and sliding connection, an endless conveyer member mounted on the frame and end section and having screens, and means guiding said end section for upward and downward movement along a straight line. 110

6. A conveyer including an inclined frame having a lower end section connected thereto with the hinge and sliding connection, an endless conveyer member mounted on said frame and section and having screens, a shaft carried by said section, sprocket wheels for the conveyer member on said shaft, 125

standards, slides supporting said shaft and inovable along said standards, and means carried by the standards for raising and lowering said slides and section.

5 7. A conveyer comprising, in combination with a sump having a depression, an inclined frame having its lower end in said sump, an endless conveyer member mounted on said frame and having screens, the receiving portion of the conveyer member working in said depression, and plates carried by said frame and extending beyond said depression for directing the water and other matter in the sump onto the upper run 10 of the conveyer member.

8. A conveyer comprising, in combination with a sump having a depression, an inclined frame having its lower end in said sump, an endless conveyer member mounted 20 on said frame and having screens, the receiving portion of the conveyer member working in said depression, side plates carried by said frame extending upwardly from the lower end portion thereof for di-

recting water and other matter in the sump 25 between said plates to the upper run of said conveyer member, and a deflector plate between said plates over the receiving portion of the conveyer member and extending in advance of said depression for deflecting the 30 liquid and matter upwardly over the upper run of the conveyer member.

9. A conveyer comprising a frame, endless sprocket chains mounted on said frame, screens between and hingedly connected with 35 said sprocket chains and having side flanges to extend upwardly at the upper run of said chains, side plates carried by the frame at the lower end portion thereof and extending upwardly above the upper run of said chains, the lower edges of said plates being disposed between said chains and flanges, and depending aprons carried by said plates and overlapping said flanges at the inner 40 sides thereof.

In testimony whereof I hereunto affix my signature.

EDWARD A. BOLF.
